Primary Examiner—Raphael Barkai*Attorney, Agent, or Firm*—Wolf, Greenfield & Sachs, P.C.[57] **CLAIM**

The ornamental design for a toy fire truck, as shown and described.

DESCRIPTION

FIG. 1 is a side elevational view of a toy fire truck showing my new design from the right side thereof, with the left side being a mirror image thereof;

FIG. 2 is a top plan view thereof;

FIG. 3 is a front elevational view thereof; and,

FIG. 4 is a rear elevational view.

The bottom is plain.

The drawings are not lined for color.
